UNITED STATES PATENT OFFICE.

CHARLES R. SMITH, OF BLOOMINGTON, ILLINOIS.

RAPID-FIRE GUN.

1,314,761.

Specification of Letters Patent.

Patented Sept. 2, 1919.

Application filed May 16, 1917. Serial No. 169,106.

To all whom it may concern:

Be it known that I, CHARLES R. SMITH, a citizen of the United States, residing at Bloomington, in the county of McLean and State of Illinois, have invented certain new and useful Improvements in Rapid-Fire Guns, of which the following is a specification, reference being had to the accompanying drawings.

10. This invention relates to fire arms, and particularly to rapid fire guns and one of the objects of the invention is the provision of a gun so constructed that it may be fired by an electric spark.
15. A further object of the invention is to provide improved means for directing a cartridge into the loading chamber of the gun and forcing the cartridge into position in the breech of the gun.
20. A further object is to provide improved means for positively actuating the breech block and to provide means for holding the cartridge in place until the breech block has shifted into a position behind the cartridge.
25. A further object is to provide improved means for ejecting the cartridge after the projectile has been discharged and in this connection to provide means for positively preventing the exploded shell from passing back into the rear end of the loading chamber and provide improved means for permitting the forward movement of the cartridge into position for loading.
30. Other objects will appear in the course 35 of the following description.

My invention is illustrated in the accompanying drawings, wherein:—

Figure 1 is a longitudinal sectional view of a rapid fire gun constructed in accordance with my invention and showing the gun at the moment when a cartridge has just been forced home in the breech;

Fig. 2 is a plan view of the gun in the position illustrated in Fig. 1;

Fig. 3 is a top plan view, the barrel, the loading chamber and a portion of the frame being in section and the parts being in the position shown in Figs. 1 and 2;

Fig. 4 is a top plan view, the barrel and loading chamber being in section and showing the gun in its firing position;

Fig. 5 is a section on the line 5—5 of Fig. 2;

Fig. 6 is an elevation of the breech block; Fig. 7 is a section on the line 7—7 of Fig. 3;

Fig. 8 is a fragmentary horizontal section on an enlarged scale of the parts illustrated in Fig. 3;

Fig. 9 is a fragmentary vertical section through a portion of the barrel and the loading chamber showing the manner in which the cartridge is ejected;

Fig. 10 is a fragmentary section on the line 10—10 of Fig. 4 showing a means for shifting the cartridge forward along the trough 53 upon the forward movement of the gun;

Fig. 11 is a perspective view of the ejector 37;

Fig. 12 is a fragmentary vertical sectional view through the rear end of the barrel 10;

Fig. 13 is a side elevation of the breech block and the rail engaging means retracted.

The gun which I have illustrated is of that type wherein the recoil of the gun shifts the barrel rearward against the force of a compression spring and this rearward movement of the gun acts to discharge the spent cartridge or shell and to reload the gun, the gun being automatically fired when the spring has returned it to its firing position.

In the accompanying drawings, 10 designates the barrel of the gun which is of any suitable construction and has, of course, a longitudinally extending bore. Attached to the barrel and extending rearward therefrom is the loading chamber 11, which is tubular and extends rearward and at its rear end is adapted to abut against the tubular frame 12, the rear end of which is contracted and closed by a plug 13, or in any other suitable manner.

The barrel is mounted upon longitudinally extending rails 14, these rails being spaced from each other, and the rear or enlarged end of the barrel 10 resting upon these rails and sliding thereon. Any suitable means may be provided for holding the barrel to the rails, but I have illustrated for this purpose a downwardly extending member such as a slide 15, provided with a cross head 16 engaging on the under side of the rails. I do not wish to be limited to the details of this construction. Disposed

- beneath the gun and beneath the rails 14 are tubular members, each formed of two sections 17 and 18 having telescopic engagement with each other. The barrel 10 of the gun is attached to the section 18 in any suitable manner, so that the section 18 and the gun barrel move together. This section 18 telescopes over the section 17, which is rigidly supported, and disposed within the tubular chamber formed by the sections 17 and 18 is a coiled compression spring 19. The forward and rear ends of the barrel 10 are connected to the sections 18 by means of the cross head 16 and of the member 16^a. It is obvious that when the barrel 10 moves rearward, it will compress the spring 19 and that as soon as the recoil force has been spent, the spring 19 will cause the barrel to move forward again to its initial position. I do not wish to limit myself to any particular frame for the gun, as this will be modified in many ways and I have simply illustrated the essential details of the gun. The rails 14 of the gun may be mounted upon a tripod, or any other suitable supporting means, depending upon the surface in which the gun is used.
- In advance of the breech 20 of the gun, the barrel is slotted as at 21 and operating through this slot is a breech block 22 illustrated in detail in Fig. 6. This breech block has sliding movement transversely through the rear end of the barrel and when in one position entirely closes the breech and in another position opens the breech. The details of the breech block will be stated later, but the means for actuating the breech block and automatically shifting it into its operative and closed position includes the two spaced rails or guides 23 mounted upon outwardly projecting members 24 or brackets forced to the frame of the gun. These rails 23, for a distance, extend parallel to the axis of the gun barrel and then extend inward and forward at an inclination, as at 25 and then extend again parallel with the gun barrel as at 26. The space between the rails 23 forms a guide slot and the breech block is provided with a lateral prolongation 27 having a laterally projecting lug engaging in this slot. Preferably this lug 28 is mounted so that it may be shifted out of engagement between the rails 23 but is normally held in engagement between these rails and I have illustrated this lug 28 as mounted upon a swinging member 29 having a handle 30, this swinging member being urged in one direction by a spring 31, which acts to hold the lug in its operative position. The extremity of the extension 27 is provided with a handle 32 whereby the breech block, when the lug is disengaged from the rails 23, may be manually withdrawn from the barrel of the gun, or manually closed or opened. The handle 30 is

angular in form so as to provide a blade 30^a which is rotatable upon the lug 28 so that this blade may be turned into a slot 22^a formed in the breech block whereby to lock the lug 28 in its outwardly projecting position, as illustrated in Fig. 6. When projected outward this lug 28 engages between the rails 23 and then the breech block cannot be manually withdrawn, but by rotating the handle 30 the blade 30^a is released from its engagement with the slot 22^a and then the lug 28 may be withdrawn from its engagement between the rails and the breech block be withdrawn by the handle 32.

Disposed within the breech block is a plug 33 of insulating material, which is adapted to contact with the primer of the cartridge and which forms a spark plug. Passing into and through this electric plug 33 is an electric wire 34 leading to a coil box A, the primary coil of which is connected to a suitable source of electricity and to a switch whereby a high tension current may be caused to pass into the spark plug, the spark formed thereby causing the explosion of the cartridge. It will be seen that as the gun moves forward to its firing position, the inclined portion 25 of the guides 23 will cause the inward movement of the breech block to its fully closed position just prior to the firing of the cartridge, as shown in Fig. 4, and that upon the return movement of the barrel under the recoil, the inclined portions of the rails will cause a retraction of the breech block and hold the breech block retracted until the gun again moves forward so that the breech block is engaged by the inclined portion 25 and caused to close. As illustrated in Fig. 12, the cartridge a is perforated at its end as at e. This perforation is covered by a slip of paper or other suitable material c. When the spark jumps from the extremity of the wire 34, the spark will penetrate this paper c and ignite the charge.

For the purpose of holding the cartridge in the gun, I provide a detent or cartridge latch 35, which operates within the slot 21 for the breech block, this detent 35 being connected to a spring 36 which urges the detent inward. Now when the breech block moves laterally into the gun barrel, it will contact with this detent 35 and shift the detent out of the way, so as to fully close the breech of the gun, as in Fig. 4. As soon as the breech block is retracted the detent 35 will swing back into normal position. The rear face of the detent is inclined so as to permit the passage of the cartridge by the detent and when once the cartridge is in place within the gun barrel, the detent springs back over the rim of the cartridge holding it firmly in place. Also disposed within the breech portion of the barrel and movable longitudinally across the slot 21, 130

is an ejector ring 37 which has an internal diameter just the size of the body of the cartridge, but less than the rim of the cartridge and at one point in its diameter this 5 ring is operatively connected to a longitudinally movable plunger 38 operating within a bore formed in the barrel, there being a spring 39 which urges this plunger rearward and urges the ejector ring 37 rearward 10 and against a stop 37^a. The front wall of the slot 21 is cut away as at 40 to accommodate this ejector ring. Now when the breech block is retracted, it releases this 15 ejector which forces the empty shell rearward into the loading chamber 11 from which it is ejected by means which will be hereafter described. By referring to Fig. 6, it will be seen that the breech block is cut away at 41, thus providing two longitudinally extending parallel legs 42. The 20 forward face of the breech block is formed with an inclined portion 43, which is adapted to engage the inclined face of the detent 35 and to force this detent outward in the 25 manner heretofore described, as the breech block moves inward under the action of the guides 25. Disposed within the tubular frame 12 but projecting beyond the forward end of this tubular frame is a loading 30 plunger 44. Disposed between the plug 13 and the rear end of this plunger is a coiled compression spring 45 which acts as a cushioning means for the plunger. The plunger is, relatively speaking, rigid and 35 the barrels and the loading chamber move rearward over the plunger, instead of the plunger moving into the barrel and the loading chamber. It is this plunger 44 which forces the cartridge into position within the 40 barrel.

The loading chamber 11 is cut away upon its upper face to provide an opening 46, this opening being normally closed by a door 47, which is held in its closed position 45 by a bolt, or other suitable latch engaging the butt end of the barrel. At its rear end the loading chamber 11 is open and at its forward end on its bottom the loading chamber is open as at 48. The loading 50 chamber also is formed on one side adjacent its rear end with a longitudinally extending opening 49 having outwardly extending side walls 50. Attached to one of these side walls is a spring strip 51, which extends 55 rearward and laterally and is provided on its end with a tooth 52, the under face of which is beveled upward. This spring strip 51 is deflected so as to urge the tooth downward. 60 Disposed parallel to the rails 14, that is parallel to the path of movement of the gun barrel and the loading chamber, is a trough 53, which has a width equal to the diameter of the cartridge and at its rear 65 end a chute 54 empties into the trough. At

a point just rearward of the forward end of the plunger 44, the side wall 55 of the trough 53 terminates. The other side wall 56 of the trough extends forward beyond the termination of the wall 55 and then extends inward in a curve, as at 57 and then forward. The detent 52 travels along the trough 53 and on each travel draws a cartridge forward until it reaches the deflector 57, which causes the cartridge to enter the 70 opening 49 into a position to be engaged by the plunger 44.

The operation of the gun is as follows: Assuming that the gun is in its retracted position and that a cartridge has been inserted in the breech, and the springs within the tubular members 17 and 18 cause the gun barrel to move forward, then as the barrel and the loading chamber move forward, the cartridge feeding lug 52 will engage a cartridge 80 and when the cartridge reaches the deflector 57, it will be guided laterally into the opening 55 and so into the loading chamber in advance of the plunger 44. When the breech block reaches the deflected portion of the rails 23, the breech block will be forced inward forcing open the latch 45 and extending solidly across the breech of the gun immediately behind the cartridge. At this time the circuit is gradually completed through the firing plug 33 and the electric spark will explode the cartridge. 90 The recoil of the explosion will cause the gun barrel and the loading chamber to travel back. When the breech block reaches 100 the inclined portion 25 of the rails 23, the breech block will commence to open and as soon as it is entirely open, the ejector 40 will be urged rearward throwing the spent shell out of the breech and into the forward end 105 of the loading chamber. This spent shell will drop through the opening 48 and it is positively directed through this opening by a gate 58, which is hingedly mounted on the bottom of the loading chamber and it is urged upward and forward to an inclined position by means of the spring 59. Thus the spent shell will be positively ejected through the bottom opening 48. As the barrel and loading chamber move still farther rearward, the gate 58 will come in contact with the cartridge disposed in front of the plunger 44 and upon a still farther rearward movement of the gun barrel and loading chamber, the gate will be forced downward into a position where it will bridge the opening 47 and the plunger will act to push the cartridge into position within the breech and to force forward the ejector ring 37. When the cartridge has been forced 115 fully home in the breech the latch 35 will engage over the cartridge locking it in place against the force of the spring 39. The barrel and the loading chamber have now reached their rearmost positions, the springs 120 125 130

19 are compressed to their fullest extent, and the gun barrel and loading chamber are now forced forward carrying another cartridge into position to be shifted into the 5 loading chamber, and eventually causing the closing of the breech and the firing of the gun.

I have not illustrated the gun sights, nor have I particularly illustrated the mounting 10 of the gun for the reason that these matters do not particularly pertain to my invention and may be of any suitable character. Neither do I wish to be restricted to the particular form of mount or frame, as these 15 may be obviously varied in many different ways.

Having described my invention, what I claim is:—

1. In a rapid fire gun, a recoil shifted 20 gun barrel, means for forcing a cartridge into the gun barrel upon its recoil movement, a breech block, means for closing the breech block upon the forward movement of the gun barrel, and electrically operated means for 25 exploding the cartridge when the breech block has been closed.

2. In a rapid fire gun, a recoil shifted gun barrel, means for forcing a cartridge into the gun barrel upon its recoil movement, a 30 breech block, means for closing the breech block upon the forward movement of the gun barrel, electrically operated means for exploding the cartridge when the breech block has been closed, said means including a spark 35 plug disposed in the breech block, and electrically operated means for causing a spark between the cartridge and said spark plug.

3. In a rapid fire gun, a recoil shifted gun barrel, a breech block mounted for trans- 40 verse movement through the barrel into or out of operative position, and means for shifting the breech block into operative position as the gun barrel reaches its forward-most position and for retracting the breech 45 block as the gun barrel moves rearwardly under the recoil, said means including rails extending approximately parallel to the line of travel of the gun barrel, said rails at their forward ends being inwardly deflected, the 50 breech block having sliding engagement with the said rails.

4. In a rapid fire gun, a recoil shifted gun barrel, a breech block mounted to shift transversely through the barrel into or out of 55 operative position, said breech block carrying a projected stud, a pair of guide rails extending approximately parallel to the path of movement of the gun barrel and at their forward ends being inwardly inclined toward the gun barrel and then longitudinally extended, the stud engaging between 60 said rails.

5. A rapid fire gun including a barrel 65 shiftable longitudinally, a breech block mounted for movement into or out of oper-

ative position, and means for shifting the breech block into operative position as the gun barrel moves forward and shifting the breech block out of operative position as the gun barrel moves rearward and including a 70 rail extending approximately parallel to the line of travel of the gun barrel, said rail at its forward end being deflected, the breech block having operative sliding engagement with the said rail.

6. In a rapid fire gun, a recoil shifted gun barrel open at the breech, a loading chamber attached to and movable with the said barrel and extending therefrom and open at its rear end, means for causing the 75 forward movement of the barrel after the recoil is spent, and means for shifting a cartridge into the barrel at the breech comprising a fixed plunger supported behind the loading chamber and projecting into the rear end thereof and adapted to engage a cartridge and shift it into position as the barrel moves rearward.

7. In a rapid fire gun, a recoil shifted gun barrel open at the breech, a loading 90 chamber attached to and movable with the said barrel and extending therefrom and open at its rear end, means for causing the forward movement of the barrel after the recoil is spent, and means for shifting a car- 95 tridge into the barrel at the breech comprising a fixed plunger supported behind the loading chamber and projecting into the rear end thereof and adapted to engage a cartridge and shift it into position as the barrel moves rearward, and resilient cushioning means resisting rearward movement of the plunger.

8. In a rapid fire gun, a recoil shifted gun barrel open at its rear end, a loading chamber connected to the rear end of the barrel and movable therewith, means for disposing cartridges one by one within the loading chamber, means acting upon the recoil of the gun to force a cartridge into the rear 105 end of the barrel, a breech block, means acting upon the recoil of the barrel to shift the breech block out of its operative position, said means acting upon a forward movement of the barrel to shift the breech 110 block into operative position, means for exploding the cartridge when the breech block is closed, means for ejecting the spent cartridge from the barrel into the loading chamber upon the recoil of the barrel and the retraction of the breech block, and means for discharging the spent cartridges from the loading chamber.

9. In a rapid fire gun, a recoil shifted gun barrel open at its rear end, a loading chamber connected thereto and movable therewith, a breech block shiftable into or out of operative position within the barrel, means acting upon a recoil of the barrel to shift the breech block out of operative position 125

and upon the forward movement of the barrel to shift the breech block into operative position when the barrel has reached a predetermined point in its forward movement, 5 means for then firing the cartridge, means for ejecting the spent cartridge in the barrel, as the barrel moves rearward under the action of the recoil, and means for forcing the new cartridge into the barrel comprising 10 a relatively fixed plunger operating through the loading chamber and acting to shove the new cartridge into position as the barrel and loading chamber move rearward.

10. In a rapid fire gun, a recoil operated barrel, a loading chamber fixed to and extending rearward from the barrel, means acting to force the cartridge into position within the barrel as the barrel moves rearward, resilient means for engaging the cartridge and holding it to its seat, a breech block shiftable into or out of operative position, means acting automatically to shift the breech block out of operative position as the barrel moves rearward and into operative position as the barrel moves forward, 25 said breech block in moving into said operative position shifting the cartridge holding means out of operative position, and means for exploding the cartridge when the barrel has moved forward to a predetermined position.

11. In a rapid fire gun, a recoil shifted barrel open at its rear end, the rear end of the barrel being formed to provide an annular seat surrounding the bore of the barrel, an ejector ring disposed on said seat and forming a seat for the rim of the cartridge, a spring urging said ejector rim outward, a spring actuated latch engaging with 35 the rim of the cartridge to hold the rim and ejector ring in said seat, a breech block movable into and out of operative position and engageable with said latch to shift the latch out of operative position when the breech block is shifted inward to its operative position, and means for feeding cartridges into the breech of the barrel upon the rearward movement of the barrel.

12. In a rapid fire gun, a recoil shifted barrel, a loading chamber attached to the rear end of the barrel shifting therewith, said loading chamber having an opening in its bottom, the rear end of the barrel opening into the loading chamber, a gate normally urged to an upwardly inclined position above the discharge opening of the loading chamber to thereby deflect the spent cartridge downward through said discharge opening, means disposed in the breech 55 of the gun barrel ejecting the spent cartridge therefrom, a loading plunger movable into the loading chamber through the rear end thereof and engaging the cartridge and forcing it forward toward the 60 barrel, said movement causing the gate to

close the discharge opening in the barrel and urging the cartridge into position in the rear end of the barrel.

13. In a gun of the character described, a supporting frame, a gun barrel and loading chamber mounted upon the supporting frame for longitudinal movement, a tubular chamber formed of two telescopic sections, one of said sections being operatively connected to the gun barrel and movable therewith, a spring disposed within said tubular chamber and urging the sections apart and resisting the rearward movement of the gun barrel under recoil, means for shifting a cartridge into the loading chamber as the barrel and loading chamber move forward, means for shifting said cartridge into the breech of the gun barrel as the barrel moves rearward under the recoil, a breech block, means for shifting the breech block to a closed position upon the forward movement of the barrel, means for exploding the cartridge, and means acting upon the return of the barrel to retract the breech block and eject the spent cartridge. 90

14. In a gun, a supporting frame, a barrel slidably mounted upon the frame and open at its breech, a breech block sliding into the barrel into or out of operative or inoperative position, a loading chamber attached to the rear end of the barrel and having an opening in its bottom adjacent the rear end of the barrel, and an opening in one side, a pivoted gate resiliently held in upwardly inclined position above said opening but movable into a position to bridge said first named opening, a relatively fixed plunger extending into the rear end of the loading chamber and acting to force a cartridge into the breech of the barrel, when the barrel and loading chamber are retracted, a trough extending parallel to the barrel and having the portion at its forward end deflected toward the barrel, means mounted upon the loading chamber disposed immediately rearward of the lateral opening in said loading chamber adapted to engage a cartridge in said trough, shift it forward against said deflected portion and shift the cartridge into the loading chamber through the lateral opening upon the forward movement of the gun barrel and loading chamber, means acting upon the barrel to shift the breech block into operative position after the barrel is moved to a predetermined line and acting upon a rearward movement of the barrel under the coil to shift the breech block out of operative position, and springs acting to resist the recoil of the barrel and loading chamber and urging the barrel and loading chamber forward to a firing position after the recoil is spent. 110

15. In a rapid fire gun, a shiftable gun barrel open at the breech, a loading chamber 130

extending rearward from the rear end of the breech, means for delivering cartridges into position in said loading chamber behind the gun barrel when the gun barrel is in its forward position, and means for forcing cartridges into the gun barrel comprising a relatively fixed plunger disposed behind the gun barrel and moving into and through the loading chamber upon the rearward movement of the gun barrel and in front of which the cartridges are disposed.

16. In a rapid fire gun, a recoil shifted barrel, a loading chamber having an opening in its bottom, a gate normally urged to an upwardly inclined position above the discharge opening of the loading chamber to thereby deflect spent cartridges ejected by the barrel downward through said discharge opening, means disposed in the breech of the gun barrel ejecting the spent cartridges therefrom into said loading chamber and against the gate, and means for forcing cartridges forward through the loading chamber into the breech.

17. In a gun, a supporting frame, a barrel slidably mounted upon the frame and open at its breech, a loading chamber attached to the rear end of the barrel and having an opening in one side to receive cartridges, and means for discharging cartridges into the loading chamber comprising a trough extending parallel to the barrel and having a portion at its forward end deflected toward the barrel, means mounted upon the loading chamber disposed immediately rearward of the lateral opening in said chamber adapted to engage a cartridge in the trough and shift it forward against said deflected portion and thereby shift the cartridge into the loading chamber through the lateral opening upon the forward movement of the gun barrel and loading chamber.

18. In a rapid fire gun, a barrel shiftable longitudinally, a breech block mounted for movement into or out of operative position relative to the barrel, a guide rail extending approximately parallel to the path of movement of the barrel, said guide rail intermediate its ends being inwardly inclined toward the barrel, and means operatively engaging the breech block with said guide rail to cause the breech block to shift into its closed position upon the engagement of said means with the deflected portion of the guide rail upon a forward movement of the

barrel and to cause a retraction of the breech block upon engagement of said means with the deflected portion of the rail upon a rearward movement of the barrel, said means being shiftable out of operative engagement with the guide rail to permit the breech block to be operated by hand.

19. In a rapid fire gun, a recoil shifted gun barrel, a breech block mounted for movement into and out of operative position into the barrel, a pair of guide rails extending approximately parallel to the path of movement of the barrel and at their forward ends being inwardly inclined toward the barrel and then longitudinally extended, and means carried by the breech block to slidably engage said guide rails, said means being shiftable out of operative engagement with the guide rails to permit the breech block to be operated by hand. 75

20. In a rapid fire gun, a recoil shifted gun barrel, a breech block mounted for movement into or out of operative position into the barrel, a pair of guide rails extending approximately parallel to the path of movement of the gun barrel, and having their forward ends deflected to shift the breech block into closed position, and means for operatively engaging the breech block with the rails comprising a member pivoted upon the breech block, a stud carried by said member and insertible between the rails, said stud being rotatable, and a locking member carried by the stud and rotatable therewith into or out of locking engagement 90 with the rails.

21. In a rapid fire gun, a recoil shifted gun barrel, a loading chamber having a rearward and forward movement and open at its ends and disposed in alignment with the gun barrel, means for disposing cartridges within the loading chamber as the barrel moves forward, and means acting upon the recoil of the gun to force a cartridge from the loading chamber into the rear end of the barrel and including a plunger fixed from longitudinal movement relative to the barrel and loading chamber. 95

In testimony whereof I hereunto affix my signature in the presence of two witnesses.

CHARLES R. SMITH.
